UNITED STATES PATENT OFFICE

THOMAS R. BROWN, OF ARCADIA, FLORIDA

FRUIT-MARKING MACHINE

Application filed November 9, 1929. Serial No. 405,988.

This invention relates to an improvement in fruit marking machines of the type wherein a series of printing drums are mounted for rotation with a shaft in a manner to print 5 a desired trademark or any other indicia on the fruit as it passes the rotating drums.

An important object of the invention is to provide, in a manner as hereinafter set forth, an improvement in fruit marking machines 10 wherein a plurality of impression dies bearing the desired trademark or indicia may be mounted on a single drum which is adapted to be laterally shifted with respect to the runway or track plate over which the fruit 15 travels for the purpose of selectively and expeditiously bringing one of said dies into position for marking said fruit.

Other objects of the invention are to provide a device of the aforementioned character which will be simple in construction, 20 strong, durable, efficient in its use and which may be manufactured at low cost.

Other objects and advantages of the invention will become apparent from a study 25 of the following specification, taken in connection with the accompanying drawings wherein like characters of reference designate corresponding parts throughout the several views, and wherein:—

30 Figure 1 is a view in top plan of the invention, the same being shown in assembled position.

Figure 2 is a view in front elevation thereof.

35 Figure 3 is a longitudinal sectional view taken substantially on the line 3—3 of Figure 1.

Figure 4 is a detail perspective view of the improved track plate.

40 Figure 5 is a view in side elevation of the improved die supporting drum mounted for rotation on the shaft and wherein the position assumed by said drum when shifted is indicated in dotted lines.

45 Figure 6 is an end view thereof.

Figure 7 is a sectional view taken substantially on the line 7—7 of Figure 5.

50 Referring to the drawings in detail, the reference character 1 designates an elongated horizontally disposed rotary shaft upon

which is mounted a die supporting drum designated generally by the reference character 2. The drum 2 comprises a pair of complementary sections 3 and 4 of substantially semi-circular cross-section which are 55 provided with the centrally disposed circumferentially extending collar sections 5. The collar sections 5 have extending therethrough aligned openings 6 having counter bored outer end portions 7 for the reception 60 of the clamping bolts 8 for securing the drum sections 3 and 4 upon the shaft 1. As seen most clearly in Figures 5 and 7 of the drawings, the head and nut on the bolts 8 are positioned in the counter bored portions 7 in order that the same will not project beyond the periphery of the collar 5. It is to be understood that the shaft 1 may be of any desired 65 length and any desired number of the drum 2 may be mounted thereon to correspond with 70 the capacity of the machine with which this invention is associated.

The drum 2 is mounted for longitudinal sliding movement on the shaft 1 and is keyed thereto for rotation therewith through the medium of the elongated key 9 which is embedded in the shaft 1 and extends longitudinally thereof, as clearly seen in Figures 2 and 7. It is understood, of course, that the drum 2 is provided with a longitudinally 80 extending complementary groove in opposed relation to the groove in the shaft for the reception of the projecting portion of the key 9. The drum 2 is further provided with a threaded bore 10 for the reception of a 85 spring-pressed ball detent 11 which is yieldingly seated in either one of a pair of depressions 12 on the outer face of the key 9 through the medium of the expansible coil springs 13 which are maintained under compression 90 against said ball detent 11 through the medium of the countersunk retaining screw or plug 14.

At its opposite end, the drum 2 is provided with circumferentially extending guide supporting shoulders or flanges 15—15 which extend beyond the frame of the collar 5 and are provided with spaced threaded openings 16 for the reception of securing ele- 100

ment or fastening the impression dies thereon.

A forwardly inclined track or guide plate 17 is pivotally mounted on the machine with which this invention is associated through the medium of the apertured ears 18 on its upper end and on its lower side and said track or plate extends forwardly over the drum 2. The track 17 is provided with a centrally disposed longitudinally extending slot 19 through which the die on one of the flanges 15 is to be projected and said track is further provided, on its longitudinal edges and adjacent the slot 19 with a pair of notches 20 or recesses which are co-extensive with said slot and are adapted for the reception of the die on the flange 15 which is not projected through the slot 19. The portion of the plate 17 immediately above the slot 19 is substantially V-shaped for the purpose of causing the fruit to travel over the slot 19.

In the use of the invention the parts are assembled in the position illustrated in Figures 1, 2 and 3 of the drawings and the desired impression dies (not shown) are mounted on the flanges or shoulders 15 through the medium of securing screws which extend into the threaded openings 16. The drum is then moved longitudinally on the shaft until the ball detent 11 seats in one of the depressions 12 in the key 9, it being understood, of course, that the track 17 is raised on its pivot in a manner to clear the flanges and die to permit the aforementioned longitudinal movement of the drum on the shaft. After the drum has been shifted to the desired position, the plate 17 is lowered and one of the flanges 15 with the impression die thereon will project through the centrally disposed slot 19, as clearly seen in Figure 3 of the drawings. As the fruit passes over the plate or track 17, said fruit will be guided over the slot 19 by the substantially V-shaped upper end of said track, as will be obvious and the impression will be made thereon by the die projecting through said slot. It is understood, of course, that the shaft 1 and the drum 2 are rotated for the purpose of marking the fruit as said fruit passes over the slot 19. The die and the flange of the drum which is not disposed in the slot 19 projects into one of the notches or recesses 20 and is free to rotate therein, as will be understood.

It will thus be seen that I have provided an improvement for use on fruit marking machines wherein a plurality of trademark bearing dies may be selectively positioned for printing any one of a plurality of trade-marks or other indicia on the fruit.

It is believed that the many advantages of a device constructed in accordance with this invention will be readily understood, and although the preferred embodiment of the invention is as illustrated and described, it

is to be understood that changes in the details of construction may be had which will fall within the scope of the invention as claimed.

What I claim is:

1. An improvement on fruit marking machines of the character described comprising guide tracks having a slot therein, a rotary shaft extending beneath the guide tracks, a drum mounted for longitudinal sliding movement on the shaft and for rotation therewith and longitudinally spaced die supporting flanges on the drum adapted to be selectively projected through the slot in the guide tracks. 10

2. An improvement on fruit marking machines of the character described comprising an inclined hingedly mounted guide track having a longitudinally extending slot therein, a rotary shaft extending transversely beneath the guide track, a drum mounted for longitudinal sliding movement on the shaft and for rotation therewith and longitudinally spaced die supporting flanges on the drum adapted to be selectively projected through the slot in the guide track. 80

3. An improvement on fruit marking machines of the character described comprising a forwardly inclined hingedly mounted guide track having a longitudinally extending slot therein and recesses on its longitudinal side edges adjacent the slot and co-extensive therewith, a rotary shaft extending transversely beneath the guide track, a drum mounted for longitudinal sliding movement on the shaft and for rotation therewith and longitudinally spaced circumferentially extending die supporting flanges on the drum adapted to be selectively projected into the slot and the recesses on the guide track. 90

4. An improvement on fruit marking machines of the character described comprising a forwardly inclined hingedly mounted guide track having a longitudinally extending slot therein and recesses in its longitudinal side edges adjacent the slot and co-extensive therewith, the portion of the guide track above the slot being substantially V-shaped, a rotary shaft extending transversely beneath the guide track, a drum mounted for longitudinal sliding movement on the shaft and for rotation therewith, and longitudinally spaced circumferentially extending die supporting flanges on the drum adapted to be selectively projected into the slot and the recesses on the guide track. 100

5. An improvement on fruit marking machines of the character described comprising a guide track having a slot therein, a rotary shaft extending transversely beneath the guide track, a drum mounted for longitudinal sliding movement on the shaft and for rotation therewith, means for retaining the drum in adjusted position on the shaft, and longitudinally spaced circumferentially extending die supporting flanges on the drum 110

adapted to be selectively projected into the slot on the guide track.

6. An improvement on fruit marking machines of the character described comprising a guide track having a slot therein, a rotary shaft extending transversely beneath the guide track, a drum mounted for longitudinal adjustment on the shaft and for rotation therewith, spring controlled means for yieldingly retaining the drum in adjusted position on the shaft, and circumferentially extending die supporting flanges on the opposite end of the drum adapted to be selectively projected through the slot in the guide track.

15 7. An improvement on fruit marking machines of the character described comprising a guide track having a slot therein, a rotary shaft extending transversely beneath the guide track, a sectional drum removably mounted for longitudinal adjustment on the shaft and for rotation therewith, co-acting yieldable means on the drum and the shaft for maintaining said drum in adjusted position on said shaft and circumferentially extending die supporting flanges mounted on said drum in spaced relation with respect to each other and adapted to be selectively projected into the slot in the guide track.

In testimony whereof I affix my signature.
